UNITED STATES PATENT OFFICE.

CHARLES E. JONES, OF CHICAGO, ILLINOIS, ASSIGNOR TO METAL ARTS & CRAFTS CO.,
OF CHICAGO, ILLINOIS, A CORPORATION OF ILLINOIS.

DESIGN FOR AN ARM FOR CHANDELIER AND BOWLS.

46,471.

Specification for Design.

Patented Sept. 29, 1914.

Application filed July 18, 1914. Serial No. 851,824. Term of patent 3½ years.

To all whom it may concern:

Be it known that I, CHARLES E. JONES, a citizen of the United States, residing at Chicago, in the county of Cook and State of Illinois, have invented a certain new, original, and ornamental Design for an Arm for Chandeliers and Bowls, of which the following is a specification, reference being had to the accompanying drawing, forming a part thereof.

The figure is a perspective view of an arm for chandeliers and bowls, showing my new design.

I claim:

The ornamental design for an arm for chandeliers and bowls as shown.

CHARLES E. JONES.

Witnesses:

V. O. LINDSTROM,
C. M. BAUMEISTER.
